UNITED STATES PATENT OFFICE.

GUY H. HOLCOMB, OF WENATCHEE, WASHINGTON.

SAFETY DEVICE FOR AUTOMOBILES.

1,115,939.

Specification of Letters Patent.

Patented Nov. 3, 1914.

Application filed December 20, 1912. Serial No. 738,606.

To all whom it may concern:

Be it known that I, Guy H. Holcomb, a citizen of the United States, residing at Wenatchee, in the county of Chelan and State of Washington, have invented certain new and useful Improvements in Safety Devices for Automobiles, of which the following is a specification.

This invention relates to safety devices for automobiles and more particularly to that class thereof employed for the purpose of controlling the operation of any one of the electric circuits, such as for instance the "sparkling circuit," the device being adapted to be locked in position when the circuit is to be maintained open or interrupted.

The invention has for one of its objects the provision of an improved mechanism for the purpose stated, comprising a movable switch-member constituting a member of said circuit, and adapted to be automatically locked in its inoperative or open position, when said member is thus moved by hand, so that then it requires the key before the member can again be moved to close the circuit.

The invention has, furthermore, for its object the provision of an improved lock-controlled device which in itself may be made of insulating material, but carries a contact maker adapted to bridge a pair of terminals which are elements of said circuit.

Further objects of the invention will hereinafter appear and be particularly defined in the claim.

The invention has been clearly illustrated in the accompanying drawings in which similar characters denote similar parts and in which—

Figure 1 is a front view of my improved device, the casing being cut away, and Fig. 2 shows the device in its "open" position.

Referring to the drawings, 10 denotes a base plate having secured thereto an insulating block 11 which carries a pair of terminals or contact points shown herein as resilient blades 12, 13, between which the current of electricity is to be established or interrupted, as the case may be. For purposes of a general description of the operation, I have shown in diagram one form of sparkling circuit, which comprises a conductor 14 leading to a primary battery B, the other terminal 15 of which is connected with one end of the primary coil 16 from which a conductor 17 leads to the contact point 13

above mentioned. The secondary circuit comprises the outer winding of an induction coil 18 which is in circuit with the spark plugs S and the timing device T, as usual. From the foregoing it will be understood that in the present instance the switching operation is intended to occur in the primary instead of the secondary circuit.

The means for connecting and disconnecting the terminals 12, 13, consists substantially of a shoe 19, made of metal and carried on the lower end of a slide member 20 which latter may be made of insulating material to prevent accidental grounding or other interfering with the proper operation of the circuit. The slide 20 is guided with its right hand end against the inner face of a casing 21 seated against the base plate and covering and inclosing the several parts of my device, and having a slot 22 in its side through which projects a handle 23 for manipulating the slide. In Fig. 1 the slide is shown in its circuit-closing position, the shoe 19 metallically connecting the points 12 and 13, while in Fig. 2 the slide is in its disconnecting position in which it is locked by the sliding bolt 24 of a lock 25 which may be of any desired construction and preferably comprises means for automatically throwing said bolt into engagement or toward the slide, as for instance a spring 26. On the other hand the lock is such that it requires a key to retract the bolt to release it from the slide, and more particularly from the notch 27 thereof.

In the present instance the left hand face of the slide has a series of teeth 28 which are adapted not only to be engaged by corresponding teeth 29 formed on the end of the bolt, but which are furthermore adapted to act as cam faces and checks to prevent any accidental upward movement of the slide, while on the other hand they are not sufficient to prevent the slide from being pushed upward by hand. Again, by this construction it will be seen that the slide can be normally pushed upward only, the teeth preventing any great amount of downward throw.

In order to prevent tampering with the slide, or the lock mechanism, I have provided a guard plate 30 covering the slot 22 at all times.

Many changes may be made in the general organization as well as in the particular construction of some of the elements consti-

tuting my improved device, without departing from the spirit of the invention, especially in the lock and in the manner of making and breaking the circuit by the movement of the slide.

I claim:—

A device of the character described comprising a pair of spaced terminals, a slide having ratchet teeth and movable in one direction to electrically connect said terminals, and movable in the opposite direction to disconnect said terminals, a spring-operated bolt having teeth normally engaging the teeth of the slide for permitting the latter

to be moved manually into inoperative position and to prevent the same from being moved into its operative position, and a key mechanism for withdrawing said bolt from its engagement with the slide to permit the manual operation of the latter in either direction.

In testimony whereof I affix my signature in presence of two witnesses.

GUY H. HOLCOMB.
